(57) **CLAIM**

I claim the ornamental design for a toy fighter, as shown and described.

DESCRIPTION

FIG. 1 is a perspective view of a toy fighter.

FIG. 2 is a front view of the toy fighter of FIG. 1.

FIG. 3 is a rear view of the toy fighter of FIG. 1.

FIG. 4 is a side view of the right side of the toy fighter of FIG. 1.

FIG. 5 is a side view of the left side of the toy fighter of FIG. 1.

FIG. 6 is a top view of the toy fighter of FIG. 1; and,

FIG. 7 is a bottom view of the toy fighter of FIG. 1.

The broken lines depict portions of the article that form no

part of the claimed design.
